UNITED STATES PATENT OFFICE

2,593,030

KEY CASE

Ragnar W. Holmgren, Flint, Mich.

Application December 29, 1949, Serial No. 135,708

4 Claims. (Cl. 70—456)

1

This invention relates to a key case and a primary object of the invention is to provide a key case adapted to hold a plurality of keys in retracted position within the key case, while allowing single keys to be extended in operative position.

Another object of this invention is to provide a key case in which the keys normally retracted within the case can be released to swing freely out of the case upon the mere pressure of a push button element, the particular key to be used being selected from the keys after they have been swung out of the retracted positions, the other keys being pressed back into the case in order that the selected key may be freely used.

Still another object of this invention is to provide a key case adapted to be made to conform with the general shape of a key and thus to hold a considerable number of keys without being unduly bulky.

Yet another object of this invention is to provide a key case in which the keys are definitely held in a predetermined arrangement thus facilitating the selection of the particular key to be used at any time.

Yet another object of this invention is to provide a key case in which keys may be reasonably easily inserted, and which will positively prevent the loss of a key from the key case.

And a last object to be mentioned specifically is to provide a key case which is relatively inexpensive and practicable to manufacture, which is safe, simple and convenient to use, and which will give generally efficient and durable service.

With these objects definitely in view, this invention resides in certain novel features of construction, combination and arrangement of elements and portions as will be hereinafter described in detail in the specification, and particularly pointed out in the appended claims, and illustrating in the accompanying drawings which form a material part of this application, and in which:

Figure 1 is a view, in perspective, of the assembled device;

Figure 2 is a vertical longitudinal sectional view taken substantially on the line 2—2 in Figure 1;

Figure 3 is another longitudinal view, taken substantially on the line 3—3 in Figure 2;

Figure 4 is a side elevational view of the device, the viewpoint being on the opposite side from the viewpoint used in Figure 1; and

Figure 5 is a sectional view taken on the line 5—5 in Figure 2 and looking in the direction of the arrows.

2

Similar characters of reference designate similar or identical elements and portions throughout the specification and throughout the different views of the drawings.

Referring now to the drawings in detail, the key case includes a body member, generally indicated at 10, comprising a back 12 and a pair of opposed spaced parallel lateral plates 14 and 16 which may be integral with the back 12. All surfaces in this member 10 are provided with rounded or beveled edges and the plates 14 and 16 are exactly similar in shape and the general shape of each may be described as conforming to the longitudinal cross-sectional shape of an egg. This egg-shape or tear-drop shape enables keys of the type illustrated in the drawing to be conveniently held in the key case. The back 12 does not extend the full length of the member 10, the back stopping short, as indicated at 18, at one end of the device, and the plate 16 is provided with a non-circular bore or socket 20 near the said one end of the device. Another bore 22 ordinarily smaller than and aligned with the bore 20 is provided in the lateral plate 14, this bore 22 having an enlarged portion 24 so that a shoulder is formed between the two portions of this bore in the plate 14.

A push pin 26 extends through the bores 22 and 24 and has an enlarged terminal 28 of a size and dimension to fit within the bore or socket 20 for axial movement therein. A threaded bore 30 is provided in the other end portion of the push pin 26 and an elongated threaded element 32 comprises a shank for a push button head 34, this shank being screwed into the threaded bore 30 and the head extending exteriorly of the lateral plate 14. A helical spring is coaxially mounted on the push pin 26 and compressed by the push button head 34 within the enlarged portion 24 of bore 22, so that the push pin 26 is biased toward the outer face of the lateral plate 14.

This lateral plate 14 may also be recessed as indicated at 38 and suitable decorative indicia or the owner's initials or the like may be applied to the plate in the recessed portion 38. Finally, a washer 40 may be threaded on the push pin 26 to abut the terminal 28. A plurality of keys 42 will also be threaded on the pin 26 when the key case is in use.

The operation of this invention will be clearly understood from a consideration of the foregoing description of the mechanical details thereof, taken in connection with the above recited objects and the disclosure in the drawing. In recapitulation, it may be noted that the spring

36 biases the push pin 26 in a direction to cause the washer 40 to bear against the adjacent key 42. The keys are all pushed toward the plate 14 and are held releasably within the case until such time as the push button head 34 is pressed, whereupon the keys may fall by gravity or may be swung out into the position of the key illustrated at the left in Figures 1 and 2. The key in this position is used in the ordinary manner and may easily be retracted into the case 10 when it shall have served its purpose.

The specific utility of the non-circular bore 20 and correspondingly shaped terminal 28 is especially noteworthy. This construction prevents rotation of the pin 28 relative to the plate 16 while allowing longitudinal movement of the pin so that the pressure of the spring 36 can be pre-adjusted as desired and so that the pin can be shifted axially during the use of the device to release the keys. The same construction also facilitates the original assembly of the key case and the replacement of keys when necessary.

It is clear that all the objects are amply achieved by this invention and further description would appear unnecessary.

Having described the invention, what is claimed as new is:

1. A case for keys including a body member generally U-shaped in cross-section and having a back and a pair of spaced parallel lateral plates, a push pin slidably and transversely mounted on said member and extending through one of said plates, a push button head on said pin and disposed outside said one plate, means to bias the pin axially toward said one plate, means on said pin adjacent the other plate for laterally engaging a key, whereby keys on said pin are releasably jammed between said means and said one plate.

2. A case for keys including a body member generally U-shaped in cross-section and having a back and a pair of spaced parallel lateral plates, a push pin slidably and transversely mounted on said member and extending through one of said plates, a push button head on said pin and disposed outside said one plate, means to bias the pin axially toward said one plate, means on said pin adjacent the other plate for laterally engaging a key, whereby keys on said pin are releasably jammed between said means and said one plate, said means including an enlarged terminal and a washer engaged by said terminal.

3. A case for keys including a body member generally U-shaped in cross-section and having

a back and a pair of spaced parallel lateral plates, a push pin slidably and transversely mounted on said member and extending through one of said plates, a push button head on said pin and disposed outside said one plate, means to bias the pin axially toward said one plate, means on said pin adjacent the other plate for laterally engaging a key, whereby keys on said pin are releasably jammed between said means and said one plate, said means including an enlarged terminal of non-circular shape and a washer engaged by said terminal, said other plate having a similarly shaped socket to receive said terminal, said push button head having a threaded shank screwed into said pin, the socket retaining said pin from rotation while allowing axial movement of the pin and adjustment of spring pressure and facilitating assembly of the key case.

4. A case for keys including a body member generally U-shaped in cross-section and having a back and a pair of spaced parallel lateral plates, a push pin slidably and transversely mounted on said member and extending through one of said plates, a push button head on said pin and disposed outside said one plate, means to bias the pin axially toward said one plate, means on said pin adjacent the other plate for laterally engaging a key, whereby keys on said pin are releasably jammed between said means and said one plate, said means including an enlarged terminal of non-circular shape and a washer engaged by said terminal, said other plate having a similarly shaped socket to receive said terminal, said push button head having a threaded shank screwed into said pin, the socket retaining said pin from rotation to facilitate adjustment of said head in said pin, said means to bias comprising a spring compressed between said push button head and said one plate.
